UNITED STATES PATENT OFFICE.

RUSSELL E. TAYLOR, OF NEW YORK, N. Y.

MACHINE FOR MAKING HAIR YARN.

1,330,455.

Specification of Letters Patent. Patented Feb. 10, 1920.

Application filed January 24, 1917. Serial No. 144,255.

To all whom it may concern:

Be it known that I, RUSSELL E. TAYLOR, a citizen of the United States, residing at 618 West 187th street, New York, in the county of New York and State of New York, have invented certain new and useful Improvements in Machines for Making Hair Yarn, of which the following is a specification, reference being had therein to the accompanying drawing.

The invention relates to machines for wrapping hairs and hair substitutes; and while it may be embodied in constructions adapted for various purposes, it is more particularly applicable to machines for wrapping fibers, such as hairs for hair yarn.

Having in view to provide an apparatus for wrapping hairs or similar fibers which shall be of the highest efficiency, objects of the invention are to provide a machine for making hair yarn in which the feed of the hairs to the spindle shall be positive and certain and which feed may be regulated to suit different lengths of hairs or fibers; which shall have parts readily accessible and removable and for which duplicate parts may be substituted; which shall not require the attention of skilled operators; which shall be capable of operation as a battery of units, each unit in itself performing the complete operation of making the hair yarn; which shall be simple, compact and economical in construction; and which shall be safe and speedy in operation. These and other objects of the invention will in part be obvious and in part be more fully explained in the following description.

The invention consists in the novel parts, improvements, combinations and features of construction herein shown and described.

The accompanying drawings which are referred to herein and form a part hereof, illustrate a preferred embodiment of the invention, the same serving in connection with the description herein to explain the principles of the invention.

Of the drawings:

Figure 1 is an end elevation of a machine constructed in accordance with the principles of the invention and shows a pair of supports upon which are mounted the parts of one operating unit;

Fig. 2 is a rear view of the machine, taken on the line 2—2 of Fig. 1, and shows the driving means located at one end of a line

of framework or supports, parts being broken away, and some in outline; Fig. 3 is an enlarged detail view of a portion of the mechanism illustrated in Fig. 1, showing the parts in the position assumed when the hair or fiber is being gripped preparatory to being extracted from the container, some parts being broken away and some outlined;

Fig. 4 is also an enlarged detail view of a similar portion of the mechanism illustrated in Fig. 1, but with the parts in the position assumed when releasing the hair or fiber to be led to the wrapping spindle, some parts being broken away and some outlined;

Fig. 5 is an enlarged side view of the mechanism used to actuate the gripper or means employed to extract the hair from the container, the parts in bold lines illustrating the position of the gripper when its ends close upon a hair, and the dot and dash outlines illustrating the rearward movement of the gripper and the position of the parts when releasing the hair;

Fig. 6 is a top plan view of the same;

Fig. 7 is a perspective view showing the shaft actuating the gripping mechanism, and illustrates more particularly the means employed for converting the rotary motion of the shaft into the quadruple movement of the deflector;

Fig. 8 is a face view of a well known form of bobbin spindle or wrapper in yarn making machines and is shown as equipped with the improved guide for the hairs in their journey from the deflector to the spindle; and

Fig. 9 is an enlarged perspective view of the said guide shown in Fig. 8, different positions of the hair in its journey to the spindle being shown by the black and dot-and-dash lines.

For convenience in describing and understanding the machine and its operation, a brief general statement of the parts and their coördination and operation will be given, to be followed by a detail description of the same; and, first, it may be said that the purpose of the machine is to wrap hairs, as those of horses, or similar filaments, with thread so as to make hair yarn for use in the arts.

The hairs are first placed in a container or receptacle from which they are taken by an extracting mechanism or gripper, and then

fed into the spindle which wraps them with thread. To insure proper and certain feed of the hairs to the spindle after leaving the gripper, special instrumentalities are employed including a deflector and rollers for conducting the hairs to the guide with which the spindle is equipped, this guide rotating at speed and unfailingly guiding the hairs, straight and perpendicular, into the spindle. To strengthen the yarn and insure the continuity of its core, a continuous thread is also fed to the spindle, and the successive hairs and the core thread, as they are fed into the spindle side by side, are wrapped together by the wrapping threads from the spindle. The finished yarn is then spooled and stored.

To perform these various operations the machine comprises, properly mounted upon a framework A, a container or holder B for the hair C which is to be fed into the machine, this container being mounted upon tracks. An extracting mechanism E takes the hairs from the container for the next step in the operation of the machine, and in Fig. 3 the container is shown with its supply of hair in presentation to this extracting mechanism, the gripping fingers of which are shown in closed position upon a hair. The hair is then withdrawn from the container by the extractor or gripping mechanism E by a rearward or outward movement of the gripper, the position of the gripper at the completion of the extracting or rearward movement, and the position of the parts engaged in effecting said movement being shown in Fig. 4. In Fig. 5 the position of the extractor, when its gripping fingers have first closed upon a hair in the container, is shown in bold lines, while the position of the parts, when the extractor has been withdrawn in its rearward movement, is shown in dot-and-dash lines.

When the hair has been withdrawn a sufficient distance by this rearward movement of the extractor, the fingers of the latter open and the hair is released; and the hair is forced downwardly by a deflector G¹⁰⁸ between the rollers H¹²⁴ which are now in open position. The respective positions of the deflector G¹⁰⁸, the open rollers H¹²⁶, the hair C, and the core thread J at one period in the operation are shown in Fig. 4. The rollers then come together (the deflector G¹⁰⁸ moving out of operative position) and by revolving upon the hair continue its downward movement leading it into the guide L, shown in detail in Fig. 9, where it is caught and forced to assume a straight and perpendicular position, in which position it is fed into the spindle M, where in association with the core thread J it is wrapped by the wrapping threads O from the bobbins P arranged on the spindle, see Fig. 8. The various parts are driven from a common source

of power and they are so arranged that their operations are properly timed with relation to each other.

Referring now to the drawings in detail, there is illustrated a complete unit or mechanism for making yarn of hairs or similar filaments, said unit being made in accordance with certain features of the invention. It will be obvious from the description herein that a battery of any desired number of these units may be employed and actuated by common means. For a complete understanding of the invention, however, it is only necessary to illustrate and describe one of these units, the actuating means, and the connection between the unit and the actuating means; the method and means for installing duplicates of the unit being obvious.

The framework for the machine as shown consists of standards A¹⁴ arranged with their inner portions abutting, see Fig. 1. Any suitable number of these standards may be employed and arranged in rows side by side and at suitable intervals. The standards are preferably fastened together by bracing rods A¹⁵ and an angle beam A¹⁶, a flat bar A¹⁷, and a support A¹⁸. Upon this framework may be mounted a unit of the battery.

As before stated the hairs or filaments C which are to be wrapped and fashioned into hair yarn are stored in a suitable holder or container. Preferably, this container is in the form of an oblong receptacle B, open at both ends and at the top for the easy ingress and egress of the hair, and is of suitable dimensions. As the hairs which are to be taken from this container to form the yarn must be taken singly, it will be seen that it is desirable that the position of the container B with relation to the means for extracting the hairs from the container should be constantly varied so that a fresh and constant supply of hairs may be presented to the extracting means.

According to one feature of the invention therefore, and in the preferred embodiment thereof, means are provided for shifting the container laterally with relation to the extractor E. Such means as shown (Fig. 3) are in the form of a reciprocating frame upon which the container is removably mounted and comprising a pair of parallel rails B²¹ connected together by braces or cross pieces B¹⁹ and arranged to slide back and forth horizontally on supporting rollers B²⁷ and B²⁸ mounted in suitable brackets on the framework, the rollers B²⁸ being grooved to hold the supporting frame in place during its sliding movements. One of the cross pieces B¹⁹ (see Fig. 2) is formed with a pair of depending flanges B²² arranged to be engaged by a pin B²³, projecting forwardly from a pinion B²⁴ driven by a smaller pinion B²⁵ fixed to a fore-and-aft

shaft B^{26} which is rotated through a worm and worm gear b^{28} from a transverse shaft B^{20} . As a result of this construction, the hair container is caused to move back and forth across the central path of movement of the extractor E and thus constantly to present a fresh supply of hairs thereto, it being pointed out that the driving connections are such that this movement of the container takes place slowly and quietly so as not to interfere with the extraction of the hairs. Any other suitable form of mechanism may be employed to effect such movement of the container, that just described being only conventional. It is also to be noted that the rails B^{21} may be of any desired length and may be supported at proper intervals by braces B^{19} and collars B^{27} and rollers B^{28} , as above described, and these rails may be actuated by the single shaft B^{26} , it being unnecessary to duplicate this shaft for the various units of a battery, the shaft being usually connected with the middle unit of a battery.

It is to be observed that by keeping the hairs in a loose condition they may be more easily extracted from the container, and therefore means are provided for agitating the hairs during the lateral reciprocation of the container. As shown, a fixed table B^{31} arranged adjacent to the front end of the container B and over which the extractor advances, is provided with protuberances or lumps B^{32} , (Fig. 6) and the ends of the hairs which project from the container are thereby disturbed or agitated during the reciprocation of the container relatively to the table. In other words, in the lateral movements of the container, the contained hairs are obliged to pass over lumps or rises B^{32} which therefore loosen and separate the hairs and cause them to rub against one another. This action not only facilitates the gripping action of the extractor, but it serves to clean the hairs and rid them of all particles of dust or other natural adherences, and in addition avoids any tendency of the hairs to stick together such as would cause the presence of cavities when the hairs are withdrawn by the extractor.

Preferrably, also, suitable means are provided to keep the hairs in the central path of the gripper and, as shown, these means comprise wires B^{34} projecting laterally from the lumps B^{32} . In addition if an extracted hair should fail to be engaged by the deflector G^{108} , it will be maintained in position to be engaged thereby at its next operation notwithstanding the movement of the container.

The extractor E , which draws the hairs from the container B , includes a pair of gripper jaws and is arranged to move forwardly or inwardly toward the container, grip a hair protruding therefrom, move

rearwardly or outwardly away from the container with the hair, and then release it, such action of the extractor taking place at each cycle of operation. As shown, rigidly connected to a driving shaft E^{36} is an eccentric E^{37} which travels in a crown E^{38} having an arm E^{39} at the end of which is pivotally connected one end of a lever E^{41} , the other end of said lever being connected to a transverse rock-shaft E^{42} journaled in the framework of the machine. At the other end of said shaft E^{42} is rigidly secured a forked arm E^{43} (Fig. 2) and a companion forked arm E^{44} is rigidly secured to a parallel rock shaft E^{46} also journaled forward in the framework. Mounted in the ends of the forks of said arms E^{43} and E^{44} , which are of equal radii, are pivot pins E^{47} and E^{48} on which pins is pivotally mounted the lower gripper jaw E^{49} of the extractor, this dual pivotal connection serving to give the lower jaw E^{49} and the parts carried by it, including the upper jaw, a parallel motion in a horizontal direction toward and from the container as the parts are operated by the rotation of the shaft E^{31} . In this way the hairs are drawn endwise from the container in a substantially straight and horizontal line, which greatly facilitates the extracting operation as well as the deflecting action later to be described.

As shown, (Figs. 4 and 5) the lower gripper jaw E^{49} of the extractor carries an upward extension E^{51} which forms a seat E^{52} for a rocking pivot E^{53} of the upper gripper jaw E^{54} , which latter is normally held, by a spring E^{56} , with its front end separated from the outer end E^{57} of the lower jaw E^{49} , the rear end E^{58} of the upper jaw resting on the rear end E^{59} of the lower jaw E^{49} , all as clearly shown in Figs. 5 and 6.

The active or forward end of the upper jaw E^{54} is in the form of a needle grip E^{61} , the same being preferably slightly slotted in its gripping face so as to facilitate the secure grasping and holding of the hairs. The forward or active end of the lower jaw E^{49} is in the form of thin leaf E^{62} pointed and sharpened at its forward end E^{63} (Fig. 6) in order to adapt it to act as a wedge among the hairs C . If desired, a thumb screw E^{64} or any other suitable form of device may be arranged on upper jaw E^{54} for holding and setting the needle grip E^{61} in proper position thereon.

Upon releasing the spring E^{56} , the upper gripper member may be easily removed and if desired duplicated or the gripping end adjusted.

Electrical means are provided for actuating the extractor gripper fingers, and said means are controlled so that at predetermined periods in the movement of the extractor, the needle grip E^{61} and leaf grip E^{62} will be closed to catch a hair between

them and then opened to release the hair. The opening movement of these gripper members is preferably caused to take place near but not quite at the completion of the rearward or outward movement of the extractor, whereas the closing movement of the gripper members is preferably caused to take place slightly after the extractor begins its rearward or retreating movement away from the container, although obviously such closing movement might be effected at an earlier period, e. g. at or about the completion of the forward movement of the extractor. By having the gripper members close upon the hairs during the retreating movement of the extractor, all danger of the buckling of the hair is removed, and the extracting operations made easier and performed more gracefully than would otherwise be possible. The electrical means employed comprise a generator F⁶⁸, see Fig. 2, and an electric circuit through contacts F⁷² and F⁷³ between which is a commutator or controller F⁷⁴ mounted upon the shaft E³⁶. As the shaft E³⁶ rotates, the two-point contact piece F⁷² opens and closes the circuit in a manner presently to be described, the circuit being from one pole F⁷⁴, through contact F⁷², commutator F⁷⁴, contact piece F⁷³, through the grounded machinery F⁷⁴, to coils F⁷⁸ and F⁷⁹ of an electromagnet carried by the lower extractor jaw E⁴⁹, leading wire F⁸¹, through line F⁸², and back to the pole F⁷⁵. Upon energization caused by the closing of the circuit, the magnetic coils F⁷⁸ and F⁷⁹ act to pull down the upper jaw and close the needle grip or finger E⁶¹ upon the leaf or lower finger end E⁶³; and upon de-energization of the coils caused by the breaking of the circuit the upper jaw with its finger E⁶¹ rises under the influence of the spring E⁶⁶ which pulls down the portion of the jaw at the rear of the pivot E⁶². Due to this arrangement of the parts, the electrical means are properly synchronized with the movements of the extractor so as to effect the opening and closing of its gripper members at the periods before mentioned, it being observed that the commutator or controller F⁷⁴, which is mounted on the power driven shaft E³⁶ effecting the mechanical operations of the various parts, acts under the control of such shaft to make and break the electric circuit for energizing and de-energizing the magnetic instrumentality at the proper periods. To regulate these periods of energization and deenergization, see Fig. 2, the commutator F⁷⁴ is made in sections and each section has any desired portion of its face, as F⁸³ and F⁸⁴, respectively, insulated so as to break the circuit. As the sections are made relatively adjustable, the relative positions of the insulated portions can also be regulated at will; and it will be seen that in this manner the mak-

ing and breaking of the circuit and consequent energization and deenergization of the magnetic coils F⁷⁸ and F⁷⁹ can be regulated at will.

The actuation of the gripper members in the manner above described constitutes an important and valuable feature of the present invention, possessing numerous advantages over all prior constructions and bringing about results which could not be attained in such prior constructions. It not only greatly simplifies the construction and operation of the parts, but enables them to perform the necessary operations, which are extremely delicate, with absolute precision. As the hair is drawn from the container in a substantially horizontal position, and as the spindle is situated beneath that instant position of the hair, the deflector G¹⁰⁵ is actuated to turn the hair in the direction of the spindle and so from its horizontal to a perpendicular attitude. It will be noted also that said deflector must be so arranged as not to interfere with the extractor in its operation; and, therefore, in the preferred embodiment of the invention illustrated, the deflector is arranged to be normally in inactive position to one side of the path of movement of the extractor and to be moved into active position above such path during the rearward movement of the extractor. It then makes a downward movement across the path of movement of the extractor when the latter is withdrawn and between it and the table B³¹ for turning the hair into a perpendicular position, as shown in Fig. 7, then withdraws on the same horizontal plane to a position beneath that from which it started, and then rises to its normal inactive position.

The deflector, as shown, comprises a transverse rock shaft G rotatably mounted in proper supports and arranged beneath the shaft E³⁶. Upon said shaft E³⁶ is rigidly secured a segmental wheel G⁸⁶, having equal portions of its periphery cut away and forming on its wall G⁸⁷ two webs, G⁸⁸ and G⁸⁹, properly balancing each other. Extending outwardly from the periphery of each web and at right angles thereto is a wedge-shaped flange G⁹¹, the two flanges extending in opposite directions from each other. The side face G⁹² of each flange contacts, upon its relative thrust, with a roller G⁹³, the pair of these rollers being mounted in a support G⁹⁴ slidably mounted on a rod G⁹⁶ fixed to supports G⁹⁸ wherein the shaft E³⁶ is mounted. An extension G⁹⁷ of the support G⁹⁴ is loosely mounted on the shaft G and confined between a pair of collars g thereon. Fixed upon the shaft G between the supports G⁹⁸ of the frame is a two-arm lever G⁹⁹ between the outer ends of which is fixed a pin G¹⁰¹ passing through a slot G¹⁰² in the end of

the arm G^{103} of a crown G^{104} in which travels an eccentric G^{105} fast upon the shaft E^{36} . At the end of the shaft G is coupled a smaller shaft G^{85} by a coupling G^{106} and secured to said shaft G^{85} is a bending arm G^{107} from the outer and upper end of which extends a deflector arm G^{108} suitably grooved at its end G^{109} properly to contact with the hair and deflect it securely in its downward movement.

10 During a complete revolution of the shaft E^{36} , taking the position shown in Fig. 7 as a start, the face G^{92} of the flange G^{91} traveling in the direction indicated by the arrow G^{111} , will thrust a roller G^{113} in the direction of the arrow G^{113} for a space equivalent to the distance on the rod G^{101} and of the width of the flange G^{91} , while the cam wheel G^{105} travels until the lower end of its slot G^{102} reaches the rod G^{101} . The flange G^{91} having covered its course, the cam wheel G^{105} raises the lower lever G^{90} while the cut-off portion of the wheel G^{86} has no more effect on the horizontal movement of the support G^{94} and the deflector arm G^{108} takes its downward radial course as shown by the arrow G^{114} , when the opposite wedge face G^{92} reverses the thrust as shown by the arrow G^{117} , until the contact of the arm G^{103} at the upper end of the slot G^{102} in the rotation of the cam wheel G^{105} causes the upward radial movement shown by the arrow G^{118} . It will be seen that in this manner and by the means described the deflector arm G^{108} normally assumes the inactive position, shown in Fig. 7, to one side of the extractor, from which position it is caused to move longitudinally during the rearward movement of the extractor as indicated by the arrow G^{118} , and at or near the completion of the rearward movement of the extractor, to pursue a radial course downward as indicated by the arrow G^{114} to the position between the rollers H^{124} and H^{126} , shown in Fig. 4 and to which further allusion will be made, deflecting the hair to its proper perpendicular position during such radial course; whereupon it is withdrawn during the forward movement of the extractor out of the field of operation thereof in the direction shown by the arrow G^{117} , and then by the reverse radial movement, as shown by the arrow G^{118} , is restored to its original inactive position.

It may be noted that the operation of the parts is so timed that the deflector begins its downward deflecting movement slightly before the extractor completes its retreating movement away from the hair container and while the extracted hair is still held by the gripper fingers. In this way the initial deflecting movement of the deflector will draw the extracted hair a short distance farther from the container and at the same time carry it part way toward the feeding means, thereby insuring the positive delivery of the hair to such feeding means when

it is subsequently released by the extractor. The means for separating and closing the feed rollers H^{124} and H^{126} comprise a cam H^{119} fast to the shaft E^{36} and acting upon a lever H^{121} fixed to one end of a transverse rock shaft H^{123} , whose other end has fast thereto an arm H^{122} carrying the roller H^{124} , the latter being held in yielding engagement with the companion roller H^{126} by a spring H^{128} attached at one end to a fixed part of the machine and at its opposite end to an extension from the rock shaft (see particularly Fig. 6). The roller H^{124} is fixed to a shaft H^{127} journaled in the frame and rotated through connections with the main shaft hereinafter referred to, the first roller H^{124} being rotated by frictional engagement with the second roller and the hair which is between them and which is passed downwardly in a perpendicular position. The cam H^{119} is properly adjusted so as to bear upon the lever H^{121} and through the latter to move the roller arm H^{122} forward in time to catch the hair C between the two rollers, at the instant when the deflector arm G^{108} passes their line of contact and to swing the roller arm H^{122} backward in time to permit the deflector arm G^{108} upon its reappearance in active position to swing in its radial course downwardly, when operating upon the succeeding hair. These movements may be particularized as follows: As shown in Fig. 3, through the energization of the magnetic coils F^{78} and F^{79} , the gripper fingers E^{61} and E^{62} are closed upon the strand of hair C , and the deflector arm G^{108} is in the position shown in Fig. 7. Upon the rotation of the shaft E^{36} , the wedge face portion of the segmental wheel G^{86} will cause the deflector arm G^{108} to be moved forward in the direction of the arrow G^{113} (Fig. 7) during which time the projecting end of the cam H^{119} will approach the roller end of the lever H^{121} ; and while the extractor is receding from the container B . This condition of the parts is maintained until the extractor nears the end of its retreating movement, when on a slight further movement of the shaft E^{36} , the cam H^{119} depresses said lever H^{121} throwing back the roller arm H^{122} and forming a gap between the feeding rollers H^{124} and H^{126} , and at that moment the deenergization of the coils F^{78} and F^{79} occurs, the partly extracted strand of hair C being released from the gripper fingers which are opened by the spring E^{66} , while the deflector arm G^{108} through the action of the cam wheel G^{105} descends in the course represented by the arrow G^{114} and acquires the position shown in Fig. 4 in which are also shown the relative positions of all the parts just enumerated and of the hair C which is being led to a perpendicular position. it being remembered however that the deflector begins its

downward or deflecting movement before the extracted hair is released by the gripper fingers. The cam H^{119} having a short actuating period, the lever H^{121} under the action of the spring H^{128} , see Fig. 6, quickly returns the arm H^{122} , bringing the roller H^{124} in contact with the driven roller H^{126} before the conducted portion of the hair C is relieved from the deflector arm G^{108} .

From the position of the parts as shown in Fig. 4 to the lowermost position of the deflector arm G^{108} , which latter position is assumed by the further rotation of the shaft E^{36} , the reciprocating movement of the 15 turn of the parts to their respective points of departure is effected in the completion of the revolution of the said shaft E^{36} , during which time the deflector arm G^{108} makes the two movements, respectively, withdrawing it from the field of the feeding operation and restoring it to its normal inactive position, as shown by the arrows G^{117} and G^{118} .

It is a grave defect in machines for making hair yarn that the hair is not guided 20 into the mouth of the spindle positively, and because of this defect the yarn is broken frequently and is liable to have many imperfections besides fouling the parts of the machine with the hairs and thus interfering with the operation of the machine and its output. Means are therefore provided for guiding positively the hair into the mouth of the spindle, and preferably and as shown 25 this means comprises a rotating spiral guide L^{132} . This guide should be arranged in position suitable to guide the hair into the mouth of the rotating spindle, and in the particular embodiment of the invention illustrated, see Fig. 9, it is shown as supported some distance above the spindle mouth by means of uprights L^{133} fixed on a collar L^{134} mounted on the spindle M with which it rotates. With this form of rotating construction the hair is guided positively to the mouth of the spindle where it is wrapped with the core thread J by the threads O from the bobbins P in an obvious manner. The core thread J is fed from a bobbin J^{142} suitably located as on the support J^{143} . As the hair wrapping or covering operation takes place within the spindle slightly below the mouth thereof, it will be seen that the hair must be under very positive control in order to enter the spindle 50 mouth. Actual practice has shown that the spiral member L^{132} will accomplish this result unfailingly, acting by its high speed of rotation to draw the hairs instantaneously into the axis of rotation of the spindle and guiding them straight into the spindle mouth. It may also be noted that the sweep of the spiral member is much greater in radius than that of the rotating spindle so that even under the most abnormal conditions (as when a hair assumes such an in-

clined position as shown in Fig. 9) it will nevertheless be caught and drawn into the center of the spiral and thus caused to enter the mouth of the spindle. This arrangement also constitutes an important and valuable feature of the present invention, being the first device of its kind which can be relied upon absolutely to insure the delivery of the hairs to the spindle for the covering operation.

Means are provided to dispose of any excess or misshaped hairs which by any chance may reach the guide L^{132} , as shown, this disposition being effected by giving the guide at a convenient portion thereof, as at L^{135} , 75 a knifelike edge, this edge by reason of the rapid rotation of the spindle and guide immediately severing any such superfluous or misshaped hairs, the extra portions dropping from the spindle. In other words the spiral guide is provided with a cutter and trims the hairs as they are guided from the feed rolls to the spindle, thereby insuring the complete wrapping or covering of the hair about the traveling core thread. The 80 spindle is operated from a pulley M^{144} connected to the main shaft R^{146} as shown in Fig. 1, a belt tightener M^{147} being provided. It is obvious that the operation of the spindle may be discontinued at any time by releasing the belt tightener M^{147} . Obviously, 85 the spindle and accessories are duplicated for each unit.

As the wrapped thread leaves the spindle M , it passes under a guide roll N^{136} and is wound around the spool N^{140} which is frictionally rotated by a sleeve on a shaft N^{138} journaled in suitable brackets N^{139} secured by bolts or other fastening devices N^{141} to the framework. The guide roller N^{136} is 100 arranged to rotate idly in arms depending from a supporting bracket N^{137} , which latter also supports a guide or eye-piece N^{135} reciprocated back and forth thereon in the well-known manner to traverse the thread 105 across the spool N^{140} .

The driving connections to the various parts have been partly described above but may be summarized as follows:

As above stated, the spindle M is rotated 115 directly from the main driving shaft R^{146} by a large pulley M^{144} connected by a belt M^{143} to a much smaller pulley M^{142} fixed to the lower end of the spindle, whereby the latter is rotated at high speed. The connections between the main shaft and the driven shaft E^{36} are best shown in Figs. 1 and 2. As there illustrated, the main shaft is provided with a spur gear T^{158} meshing with a similar gear T^{157} fixed to an intermediate 120 shaft T^{156} . This latter shaft is further provided with a small gear T^{160} meshing with a much larger gear T^{164} rotatable on a pendant arm T^{163} and meshing in turn with a slightly larger gear T^{166} fast upon a trans- 125

verse shaft T^{152} from which the arm T^{153} is loosely suspended. Alongside the gear T^{155} the shaft T^{152} is provided with a sprocket wheel E^{162} connected by a chain E^{163} to a small sprocket wheel E^{164} fixed to the shaft E^{36} , thus completing the connections to the latter, which effects the to and fro movements of the extractor E and the roller H^{124} as well as the operation of the deflector G^{108} in the manner before described. The rotation of the shaft H^{127} carrying the feed roller H^{126} is effected by means of a sprocket wheel H^{151} fast to the shaft and connected by chain H^{152} to a similar sprocket wheel H^{153} on the shaft B^{20} before referred to, this shaft B^{20} being driven through spur-gearing H^{154} from the shaft T^{152} and which as just described is driven from the main shaft. The shifting of the container B from the shaft B^{20} has already been described so that the operating connections from the main shaft will be clear without further description. To effect the rotation of the spool N^{140} , its driving shaft N^{138} has a sprocket wheel N^{139} connected by a chain N^{140} to a smaller sprocket wheel N^{141} fixed to a shaft N^{142} . This shaft N^{142} is driven through a train of gearing N^{143} from a shaft N^{150} journaled in the lower end of a pendant arm N^{161} and having a sprocket wheel N^{149} connected by a chain T^{159} to a larger sprocket wheel on the shaft T^{152} driven from the main shaft as above noted. The various parts are thus driven by positive connections from the main shaft R^{146} , and it is pointed out that these connections are so proportioned and related as to effect the operations of the different parts in timed relation. While the foregoing mechanism is particularly suitable for the intended operations, it is evident that various other forms of mechanism might be employed to carry out the desired operations.

If it should be desired to change the speed of the parts, this may be done by removing the gear T^{154} and substituting another of the desired ratio, it being remembered that the gear is mounted on the arm T^{153} which may be swung outwardly at will to permit such substitution. Similarly if it be desired to alter the relative speed of the spooling mechanism, the gear N^{148} carried by the swinging arm N^{161} may be removed and another of the desired ratio substituted therefor. In this way the parts may be freely adjusted to accommodate hairs of different lengths as well as hairs of different thicknesses or form, etc.

It will be obvious from the foregoing description that many units may be employed, all deriving their power from the main shaft R^{146} . It will be obvious also that on the shaft E^{36} may be arranged any number of gripping mechanisms; on the deflector

shaft G^{85} may be arranged a deflector arm G^{108} for each unit; and on the roller shaft H^{127} , a driven roller H^{126} may be provided for each unit,—the companion roller and its arm and mechanism being also adapted to be duplicated on each gripping mechanism; and a spooling apparatus may be provided for each unit; as also a spindle drive. It will also be obvious that the electrical circuit for energizing the magnetic coils which actuate the gripper fingers may be used for any desired number of units, the magnetic coils being adapted to be duplicated on each unit. It is believed that the operation of the machine as a whole has been fully set forth in the foregoing description and therefore no particular further description will be necessary.

A machine for making hair yarn constructed in accordance with the foregoing description will carry out the objects of the invention, as heretofore stated, and will possess other advantages which will be apparent to those skilled in the art.

The invention in its broader aspects is not limited to the precise construction shown and described nor to any construction in which the same has been or may be embodied, as many changes may be made in the details thereof without departing from the main principles of the invention or sacrificing its chief advantages.

I claim:

1. In a machine of the character described comprising hair covering means, the combination with a hair container and an extractor, one of said parts being movable toward and from the other to draw the hairs from the container for delivery to the covering means, of a deflector movable between the container and extractor in their separated condition to direct the extracted hairs toward the covering means.

2. In a machine of the character described comprising hair covering means, the combination of a hair container, a movable extractor to draw the hairs therefrom for delivery to the covering means, and a deflector movable across the path of movement of the extractor to direct the extracted hairs toward the covering means.

3. In a machine of the character described comprising hair covering means, the combination of a hair container, an extractor movable in a horizontal direction to draw the hairs from the container for delivery to the covering means, and a deflector movable in a vertical direction to direct the extracted hairs toward the covering means.

4. In a machine of the character described comprising hair covering means, the combination of a hair container, a movable extractor to draw the hairs therefrom, means for feeding the hairs to the covering means, and a deflector movable relatively to the ex-

- tractor to carry the extracted hairs into the field of action of the feeding means.
5. In a machine of the character described comprising a vertically arranged hair covering spindle, the combination with a hair container and an extractor, one of said parts being movable toward and from the other in a horizontal direction to draw the hairs from the container, of underlying means 10 for feeding the extracted hairs to the covering spindle, and a deflector movable vertically between the extractor and container in their separated condition to carry the leading ends of the extracted hairs downwardly into the field of action of the feeding means.
6. In a machine of the character described comprising hair covering means, the combination with a hair container and an extractor, one of said parts being movable toward and from the other to draw the hairs from the container, of means for feeding the extracted hairs to the covering means, and a deflector movable between the container 25 and extractor in their separated condition to carry the extracted hairs into the field of action of the feeding means.
7. In a machine of the character described comprising hair covering means, the combination of a hair container, an extractor to draw the hairs therefrom, a pair of co-acting members for feeding the extracted hairs to the covering means, means for separating and closing said members periodically, and a movable deflector acting in the separated condition of the feed-members to carry the extracted hairs therebetween.
8. In a machine of the character described comprising hair covering means, the combination of a hair container, an extractor to draw the hairs therefrom, a pair of co-acting members for feeding the extracted hairs to the covering means, means for separating and closing said members periodically, and a deflector movable through said members in their separated condition to carry the extracted hairs therebetween.
9. In a machine of the character described comprising hair covering means, the combination of a hair container, an extractor to draw the hairs therefrom for delivery to the covering means, and a deflector movable in one direction to engage an extracted hair and then in a different direction to direct it toward the covering means.
10. In a machine of the character described comprising hair covering means, the combination of a hair container, an extractor to draw the hairs therefrom, a pair of co-acting members for feeding the extracted hairs to the covering means, a deflector movable in one direction to engage an extracted hair and then in a different direction to carry it into the field of action of the feed-members, and means for separating the feed-members in time to receive the extracted hair from the deflector and thereafter closing said members to continue the feeding action.
11. In a machine of the character described comprising hair covering means, the combination of a hair container, an extractor to draw the hairs therefrom, a pair of co-acting members for feeding the extracted hairs to the covering means, a deflector movable in one direction to engage an extracted hair and then in a different direction through the feed-members to carry the hair therebetween, and means for separating the feed-members in time to permit the passage therethrough of the deflector and thereafter closing said members to continue the feeding action.
12. In a machine of the character described comprising hair covering means, the combination of a hair container, a movable extractor to draw the hairs therefrom for delivery to the covering means, a deflector movable toward the extractor and then across its path of movement so as first to engage an extracted hair and then direct it toward the covering means, and mechanism for effecting the movements of the parts in timed relation.
13. In a machine of the character described comprising hair covering means, the combination of a hair container, a movable extractor to draw the hairs therefrom for delivery to the covering means, a deflector movable in four different directions, first toward the extractor, then across its path of movement, then away from such path, and finally back to its original position, and mechanism for effecting the movements of the parts in timed relation.
14. In a machine of the character described comprising hair covering means, the combination of a hair container, a movable extractor to draw the hairs therefrom, a pair of co-acting members for feeding the extracted hairs to the covering means, one movable into and out of engagement with the other, a deflector movable across the path of movement of the extractor and through the feed-members in their separated condition to deliver the extracted hairs thereto, and mechanism for effecting the movements of the parts in timed relation.
15. In a machine of the character described comprising hair covering means, the combination of a hair container, a movable extractor to draw the hairs therefrom and comprising gripper members movable to open and closed position at predetermined periods, a pair of co-acting members for feeding the extracted hairs to the covering means, one of said members being movable into and out of engagement with the other, a deflector movable across the path of movement of the extractor and through the feed-

members in their separated condition to deliver the extracted hairs thereto, and mechanism for effecting the movements of the various parts in timed relation.

- 5 16. In a machine of the character described comprising hair covering means, the combination of a hair container, a movable extractor to draw the hairs therefrom and comprising gripper members movable to 10 open, and closed position at predetermined periods, a pair of coacting members for feeding the extracted hairs to the covering means, one of said members being movable into and out of engagement with the other, 15 a deflector movable across the path of movement of the extractor and through the feed-members in their separated condition to deliver the extracted hairs thereto, and mechanism for effecting the movements of the 20 various parts in timed relation, the said mechanism including electrical means for effecting the opening and closing movements of the extractor gripper members.

17. In a machine of the character described comprising hair covering means, the combination of a hair container, a movable extractor to draw the hairs therefrom and comprising gripper members movable to open and closed position at predetermined 25 periods, a pair of coacting members for feeding the extracted hairs to the covering means, one of said members being movable into and out of engagement with the other, a deflector movable across the path of movement of the extractor and through the feed-members in their separated condition, to deliver the extracted hairs thereto, and mechanism for effecting the movements of the various parts in timed relation, the said 30 mechanism including a power-driven shaft, connections from said shaft to the extractor, movable feed-member and deflector respectively, an electrical device carried by the extractor to effect the opening and closing of 35 its gripper members, and a controller mounted on the power-driven shaft and connected in circuit with the electrical device.

- 40 18. In a machine of the character described comprising hair covering means, the combination of a hair container, a movable extractor to draw the hairs therefrom, means 45 for feeding the extracted hairs to the covering means, a deflector movable across the path of movement of the extractor to carry the extracted hairs positively into the field of action of the feeding means, and means for positively guiding the hairs from the feeding means to the covering means.

- 45 19. In a machine of the character described comprising hair covering means, the combination of a hair container, a movable extractor to draw the hairs therefrom, means for feeding the extracted hairs to the covering means, a deflector movable across the 50 path of movement of the extractor to carry

the extracted hairs positively into the field of action of the feeding means, and means for positively guiding the hairs from the feeding means to the covering means, the said guiding means comprising a rotating 55 spiral member to engage the hairs as they pass from the feeding means and center them in proper relation to the covering means.

20. In a machine of the character described comprising hair covering means, the combination of a hair container, an extractor to draw the hairs therefrom and comprising relatively movable gripper members, means for effecting the opening and closing 60 movement of said members, a movable deflector to engage an extracted hair and direct it toward the covering means, and means for actuating the deflector, the said means being operative to initiate the deflecting movement of the deflector while the extracted hairs are still held by the gripper members, for the purpose described.

21. In a machine of the character described comprising hair covering means, the combination of a hair container, an extractor movable toward and from same to draw the hairs therefrom and comprising relatively movable gripper members, means for opening and closing said gripper 65 members, means for feeding the extracted hairs to the covering means, a deflector movable between the extractor and container to carry an extracted hair into the field of action of the feeding means, and means for 70 actuating the deflector, the said actuating means being operative to initiate the deflecting movement of the deflector while the extracted hair is still held by the gripper members, whereby said hair will be drawn 75 farther from the container before it is released by the extractor and its delivery to the feeding means thus positively insured.

22. In a machine of the character described, the combination of a hair container, 80 an extractor to draw the hairs therefrom, and means to engage and agitate the hairs within the container to loosen and separate them, for the purpose described.

23. In a machine of the character described, the combination of a hair container, an extractor to draw the hairs therefrom, means for moving the container laterally in relation to the extractor, and means engaged by the hairs in the lateral movements 85 of the container to agitate and loosen them for the purpose described.

24. In a machine of the character described, the combination of a hair container adapted to hold the hairs with their ends 90 protruding therefrom, an extractor to draw the hairs therefrom, means for moving the container laterally in relation to the extractor, and a fixed table upon which the protruding ends of the hairs rest, said table 95

- being formed with lumps or rises to engage and agitate the hairs in the movements of the container.
25. In a machine of the character described, the combination of a hair container adapted to hold the hairs with their ends protruding therefrom, an extractor movable toward and from the container to draw the hairs therefrom, means for moving the container laterally in relation to the extractor, and a fixed table upon which the protruding ends of the hairs rest in the movements of the container, the said table being formed with means to engage an extracted hair and confine it in a central position irrespective of the movement of the container.
26. In a machine of the character described comprising hair covering means, the combination of a container to hold the hairs in horizontal position, an extractor disposed horizontally and mounted to move toward and from the container with a parallel motion, and means for effecting the movement of the extractor; whereby the hairs will be drawn endwise from the container in a substantially straight and horizontal line.
27. In a machine of the character described comprising hair covering means, the combination of a hair container, an extractor movable toward and from the container, a pair of parallel swinging arms of equal radii pivotally connected to the extractor near its opposite ends, and means for effecting the movement of the extractor.
28. In a machine of the character described, the combination of a hair container, an extractor movable toward and from the container and comprising a pair of gripper members, a pair of swinging arms of equal radii pivotally connected to one of said gripper members near its opposite ends, the other gripper member being pivotally mounted on the companion member, means for effecting the movement of the extractor, and means for rocking the pivoted gripper member at the proper times in the movements of the extractor to effect the gripping and releasing action thereof.
29. In a machine of the character described, the combination of a hair container, an extractor movable toward and from the container and comprising a pair of gripper members, a pair of swinging arms of equal radii pivotally connected to one of said gripper members near its opposite ends, the other gripper member being pivotally mounted on the companion member, means for effecting the movement of the extractor, and means for effecting the opening and closing movements of its gripper members, the last said means comprising a spring for rocking the pivoted member in one direction, and an electrically energized device carried by the other member for rocking the pivoted member in the opposite direction.
30. In a machine of the character described, the combination of a hair container, an extractor movable toward and from the container and comprising a pair of gripper members, a pair of swinging arms of equal radii pivotally connected to one of said gripper members near its opposite ends, the other gripper member being pivotally mounted on the companion member, means for effecting the movement of the extractor, and means for effecting the opening and closing movements of its gripper members, the last said means comprising a spring acting on the pivoted member to rock it to open position, a stop to arrest it in such open position, and an electrically energized device carried by the other member for rocking the pivoted member to closed position.
31. In a machine of the character described comprising hair covering means, the combination of a hair container, a movable extractor to draw the hairs therefrom for delivery to the covering means and comprising relatively movable gripper members, and electrical means synchronized with the movement of the extractor to control the opening and closing movements of its gripper members at the proper periods.
32. In a machine of the character described comprising hair covering means, the combination of a hair container, a movable extractor to draw the hairs therefrom for delivery to the covering means and comprising relatively movable gripper members, a magnetic instrumentality carried by the extractor for effecting the opening and closing movements of its gripper members, a source of electricity, a circuit connecting said source and the magnetic instrumentality, and means controlled by the movement of the extractor to make and break the circuit for energizing and deenergizing the magnetic instrumentality at predetermined periods in the movements of the extractor.
33. In a machine of the character described comprising hair covering means, the combination of a hair container, a movable extractor to draw the hairs therefrom for delivery to the covering means and comprising relatively movable gripper members, a magnetic instrumentality carried by the extractor for effecting the opening and closing movements of its gripper members, a source of electricity, a circuit connecting said source and the magnetic instrumentality, and a controller included in said circuit and operated in synchronism with the movements of the extractor to energize and deenergize the magnetic instrumentality at the proper periods.
34. In a machine of the character described comprising hair covering means, the combination of a hair container, a movable extractor to draw the hairs therefrom for delivery to the covering means and comprising

- ing relatively movable gripper members, a magnetic instrumentality carried by the extractor for effecting the opening and closing movements of its gripper members, a source 5 of electricity, a circuit connecting said source and the magnetic instrumentality, and a controller included in said circuit and operated in synchronism with the movements of the extractor to energize and de- 10 energize the magnetic instrumentality at the proper periods, the said controller being adjustable to regulate the periods of energization and deenergization of the magnetic instrumentality.
- 15 35. In a machine of the character described comprising hair covering means, the combination of a hair container, a movable extractor to draw the hairs therefrom for delivery to the covering means and comprising relatively movable gripper members, a power-driven shaft operatively connected to the extractor to effect the movements thereof, a magnetic instrumentality carried by the extractor for effecting the opening and 20 closing movements of its gripper members, a source of electricity, a circuit connecting said source and the magnetic instrumentality, and a controller included in said circuit and mounted on the power-driven shaft 25 to energize and deenergize the magnetic instrumentality at the proper periods in the movements of the extractor.
- 30 36. In a machine of the character described comprising hair covering means, the combination of a hair container, a movable extractor to draw the hairs therefrom for delivery to the covering means and comprising relatively movable gripper members, a power-driven shaft operatively connected to 35 the extractor to effect the movements thereof, a magnetic instrumentality carried by the extractor for effecting the opening and closing movements of its gripper members, a source of electricity, a circuit connecting said source and the magnetic instrumentality, and a controller included in said circuit and mounted on the power-driven shaft 40 to energize and deenergize the magnetic instrumentality at the proper periods in the movements of the extractor.
- 45 37. In a machine of the character described comprising hair covering means, the combination of a hair container, an extractor for drawing hairs therefrom for delivery to the covering means, and electrical means synchronized with the extracting operations to effect the gripping and releasing action of the extractor at the proper periods.
- 50 38. In a machine of the character described comprising hair covering means, the combination of a hair container, an extractor for drawing hairs therefrom for delivery to the covering means, and electrical means including a magnetic instrumentality energized and deenergized at predetermined 55 periods in the extracting operations to effect the gripping and releasing action of the extractor.
- 59 39. In a machine of the character described comprising hair covering means, the combination of a hair container, an extractor for drawing hairs therefrom for delivery to the covering means, and electrical means to effect the gripping and releasing action of the extractor, the said means including a magnetic instrumentality associated with the extractor, a source of electricity, a circuit connecting said source and magnetic instrumentality, and a controller included in said circuit and acting at predetermined 65 periods in the extracting operations to energize and deenergize the magnetic instrumentality.
- 64 40. In a machine of the character described comprising hair covering means, the combination of a hair container, an extractor for drawing hairs therefrom for delivery to the covering means, and electrical means to effect the gripping and releasing action of the extractor, the said means including a magnetic instrumentality associated with the extractor, a source of electricity, a circuit connecting said source and magnetic instrumentality, and a controller included in said circuit and acting at predetermined 75 periods in the extracting operations to energize and deenergize the magnetic instrumentality.
- 79 41. In a machine of the character described comprising hair covering means, the combination of a hair container and an extractor comprising relatively movable gripper members, one of said parts being movable toward and from the other to draw the hairs from the container for delivery to the covering means, with means operative to effect the closing action of the gripper members after the movable part begins its retreating movement, for the purpose described.
- 84 42. In a machine of the character described comprising hair covering means, the combination of a container, an extractor movable toward and from the container to draw the hairs therefrom for delivery to the covering means and comprising relatively movable gripper members, and means operative to effect the closing action of the gripper members after the extractor begins its retreating movement.
- 89 43. In a machine of the character described, the combination of hair covering means, means for passing hairs thereto, and

an intermediate rotating spiral member acting by its rotation to center and guide the passing hairs in proper relation to the hair covering means.

- 5 44. In a machine of the character described, the combination of a rotating spindle for covering the hairs, means for passing the hairs to the spindle, and a rotating spiral member arranged in advance of the spindle and acting by its rotation to center the hairs and guide them into the mouth of the spindle.

- 10 45. In a machine of the character described, the combination of a rotating spindle for covering the hairs, means for passing the hairs to the spindle, and a spiral member mounted on the spindle above the mouth thereof and acting by the rotation of the spindle to center the hairs and guide them into the spindle mouth for the covering operation.

- 15 46. In a machine of the character described, the combination of a rotating spindle for covering the hairs, means for passing the hairs to the spindle, and a rotating spiral member arranged in advance of the spindle and acting by its rotation to center the hairs and guide them into the mouth of the spindle, the said spiral member having a sweep of materially greater radius than that of the spindle mouth to insure the delivery of the hairs thereinto under the most abnormal conditions.

- 20 47. In a machine of the character described, the combination of hair covering means, means for passing the hairs thereto, a rotating spiral member arranged in advance of the covering means and acting by its rotation to center and guide the hairs in proper relation thereto, and a cutter disposed on the spiral member to trim the hairs as they are guided thereby.

- 25 48. In a machine of the character described, the combination of hair covering means, means for passing hairs thereto, and an intermediate guide having a cutter disposed thereon to trim the hairs as they are guided to the covering means.

- 30 49. In a machine of the character described, the combination of hair covering means, means for passing the hairs thereto, and intermediate means for trimming the hairs in their passage to the covering means.

- 35 50. In a machine of the character described, the combination of hair covering means, a deflector to direct the hairs toward said covering means, and mechanism for operating the deflector, the said mechanism comprising a rock shaft on which the deflector is mounted, means for shifting the shaft axially to locate the deflector in different positions, and means for turning the shaft in its different shifted positions.

- 40 51. In a machine of the character described, the combination of a movable ex-

tractor; a feeding instrumentality comprising coacting members one of which is movable toward and away from another; a deflector; and means operable upon movement of the extractor in one direction to move said deflector into position between the feeding members, said means being operable upon further movement of the extractor to pass the deflector between the feeding members, and move it out of operative relation with said feeding members.

45 52. The combination of a shaft, a bending arm arranged on said shaft, means for shifting said shaft to different longitudinal positions, and means for rocking said shaft while in said positions, whereby said bending arm may be caused to operate while the shaft is in one position and to return to normal position while the shaft is in another position.

53. The combination of a shaft, a deflector extending therefrom, means arranged to rock said shaft at pre-determined intervals, and means arranged to reciprocate said shaft between said intervals, whereby the deflector is caused regularly to move from and return to its normal position by the rocking of the shaft and to be carried into and out of operative position by the reciprocation of the shaft.

54. The combination of a shaft, a deflector extending therefrom, a cam arranged to rock said shaft at predetermined intervals, and a cam arranged to reciprocate said shaft between said intervals, whereby the deflector is caused regularly to move from and return to its normal position by the rocking of the shaft and to be carried into and out of operative position by the reciprocation of the shaft.

55. A mechanism for changing the direction of a fiber in its travel from one part of a machine to another, said mechanism comprising a shaft, a bending arm extending from said shaft and having a deflector arranged parallel to and above said shaft, a cam arranged to rock said shaft at predetermined intervals whereby the deflector is brought to a lower position and after an interval returned to its normal position, and a cam arranged to reciprocate said shaft longitudinally between the downward-and-upward and upward-and-downward movements of the deflector, whereby the deflector is brought into and out of operative position.

56. In a machine of the character described, an extractor; a deflector; electrical means for actuating the extractor; means for actuating the deflector; means for synchronizing the action of the deflector and the extractor actuating means; said means comprising a source of electricity, the means for actuating the extractor being in circuit with said source; and means for opening

and closing said circuit controlled by said extractor actuating means.

57. A machine for making hair yarn and the like comprising a source of power; a hair container; mechanism connecting said container and said source of power to move the container; an extractor comprising co-acting gripper-members movable into and out of operative relation to said container, the means for effecting this movement comprising a support, links sustaining the co-acting gripper-members on said support, and a cam and lever connection between the source of power and said gripper-members; a magnetic instrumentality associated with said gripper-members to open and close the same; a source of electricity; a circuit connecting said source and said magnetic instrumentality; and means controlled by the source of power for opening and closing said circuit.

58. A machine for making hair yarn and the like comprising a source of power; a hair container; mechanism connecting said container and said source of power to move the container; an extractor comprising co-acting gripper-members movable into and out of operative relation to said container, the means for effecting this movement comprising a support, links sustaining the co-acting gripper-members on said support, and a cam and lever connection between the source of power and said gripper-members; a magnetic instrumentality associated with said gripper-members to open and close the same; a source of electricity; a circuit connecting said source and said magnetic instrumentality; and means controlled by the source of power for opening and closing said circuit and synchronizing the action of the gripper-members with the movement of the extractor toward and away from the container.

59. A machine for making hair yarn and the like comprising a source of power; a hair container; mechanism connecting said container and said source of power to move the container; an extractor comprising co-acting gripper-members movable into and out of operative relation to said container, the means for effecting this movement comprising a support, links sustaining the co-acting gripper-members on said support, and a cam and lever connection between the source of power and said gripper-members; a magnetic instrumentality associated with said gripper-members to open and close the same; a source of electricity; a circuit connecting said source and said magnetic instrumentality; means controlled by the source of power for opening and closing said circuit and synchronizing the action of the gripper members with the movement of the extractor toward and away from the container, said means comprising a commu-

tator associated with said source of power, and electrical contact devices connecting said commutator and included in said circuit.

60. A machine for making hair yarn and the like comprising a source of power; a hair container; mechanism connecting said container and said source of power to move the container; an extractor comprising co-acting gripper-members movable into and out of operative relation to said container, the means for effecting this movement comprising a support, links sustaining the co-acting gripper-members on said support, and a cam and lever connection between the source of power and said gripper-members; a magnetic instrumentality associated with said gripper-members to open and close the same; a source of electricity; a circuit connecting said source and said magnetic instrumentality; means controlled by the source of power for opening and closing said circuit; feeding instrumentality comprising a rotatable member; and a member movable into and out of engagement therewith and governed by the movement of the extractor.

61. A machine for making hair yarn and the like comprising a source of power; a hair container; mechanism connecting said container and said source of power to move the container; an extractor comprising co-acting gripper-members movable into and out of operative relation to said container, the means for effecting this movement comprising a support, links sustaining the co-acting gripper-members on said support, and a cam and lever connection between the source of power and said gripper-members; a magnetic instrumentality associated with said gripper-members to open and close the same; a source of electricity; a circuit connecting said source and said magnetic instrumentality; means controlled by the source of power for opening and closing said circuit; feeding instrumentality comprising a rotatable member; a member movable into and out of engagement therewith and governed by the movement of the extractor; means for moving the member comprising a link upon which the member is mounted; and an arm disposed on said link and cam actuated from said source of power.

62. In a machine of the character described, means for guiding the hairs to the spindle, said means comprising a spiral frame arranged at one end of the spindle and adapted to be rotated with the spindle at high speed, a section of said spiral having a knifelike edge whereby any superfluous or misshaped hairs will be cut away from the guide or spindle.

63. In a machine of the character described; a power shaft; an extractor actuatable from said shaft into and out of operative relation to a container; a feeding in-

- strumentality; a deflector; means for moving the deflector in relation to said feeding instrumentality, said means comprising a flange member actuatable from said power shaft, a support on which the deflector is mounted; and means connecting the flange member and support to intermittently move the deflector into and out of operative relation to the feeding instrumentality.
64. In a machine of the character described; a power shaft; an extractor actuatable from said shaft into and out of operative relation to a container; a feeding instrumentality; a deflector; means for moving the deflector in relation to said feeding instrumentality, said means comprising a flange member actuatable from said power shaft, a support on which the deflector is mounted; and means connecting the flange member and support to intermittently move the deflector into and out of operative relation to the feeding instrumentality, said means comprising a bearing for said support and members mounted on the support and adapted to be engaged by a portion of the flange-member.
65. In a machine of the character described; a power shaft; an extractor actuatable from said shaft into and out of operative relation to a container; a feeding instrumentality; a deflector; means for moving the deflector in relation to said feeding instrumentality, said means comprising a flange member actuatable from said power shaft, a support on which the deflector is mounted; means connecting the flange member and support to intermittently move the deflector into and out of operative relation to the feeding instrumentality; and means for rotating the deflector support.
66. In a machine of the character described; a power shaft; an extractor actuatable from said shaft into and out of operative relation to a container; a feeding instrumentality; a deflector; means for moving the deflector in relation to said feeding instrumentality, said means comprising a flange member actuatable from said power shaft, a support on which the deflector is mounted; means connecting the flange member and support to intermittently move the deflector into and out of operative relation to the feeding instrumentality; and means for rotating the deflector support.
67. In a machine of the character described, an extractor including gripping members, one of which is movable in relation to another; means for effecting this movement; a deflector; means for effecting a relative movement between the extractor and deflector; and means for synchronizing the movement of the gripping members with the relative movement between the extractor and deflector, said means including an electrical device energized upon movement of the deflector to move one of the gripping members.
68. In a machine for making hair yarn, the combination of a gripper for extracting the hairs from the container, said gripper having fingers normally in open or inoperative position, a magnet for closing the fingers, and a commutator arranged to energize the magnet at predetermined intervals.
69. In a machine for making hair yarn, the combination of a container for the hairs, a gripper for extracting the hairs from the container with a forward and rearward movement, said gripper having fingers normally in open or inoperative position, a magnet for closing the fingers, and a commutator arranged to energize the magnet at or about the end of the forward movement of the gripper.
70. A machine for making hair yarn, including in combination a container for the hairs, an extractor for withdrawing the hairs from the container with a forward and backward movement, and means for deflecting the hair in the direction of the spindle, a shaft for operating said extracting means, a shaft for operating the deflecting means, and connections between said shafts whereby said deflecting means will be caused to operate upon the hairs between the rearward and forward movements of said extracting means.

In testimony whereof, I have affixed my signature hereto.

RUSSELL E. TAYLOR.
